UNITED STATES PATENT OFFICE.

JOHN F. O'CONNOR, OF CHICAGO, ILLINOIS, ASSIGNOR TO WILLIAM H. MINER, OF CHICAGO, ILLINOIS.

SIDE BEARING FOR RAILWAY-CARS.

1,132,610.

Specification of Letters Patent. Patented Mar. 23, 1915.

Application filed November 24, 1913. Serial No. 802,846.

To all whom it may concern:

Be it known that I, JOHN F. O'CONNOR, a citizen of the United States, residing at Chicago, in the county of Cook and State of Illinois, have invented a certain new and useful Improvement in Side Bearings for Railway-Cars, of which the following is a full, clear, concise, and exact description, reference being had to the accompanying 10 drawings, forming a part of this specification.

My invention relates to improvements in side bearings for railway cars.

The object of my invention is provide a 15 durable and efficient side bearing for railway cars.

In the drawings I have illustrated my invention as embodied in a side bearing applied to a passenger car.

20 In the drawings—Figure 1 is an end elevation of a body bolster and a truck bolster with the side bearing applied thereto embodying my invention; Fig. 2 is a plan view of the side bearings; Fig. 3 is a cross section taken on line 3—3 of Fig. 2; Fig. 4 is a longitudinal section taken on line 4—4 of Fig. 2.

Referring to the drawings, the numerals 5, 5 represent body bolsters connected by the body side bearing bridge 6.

30 The numeral 7 represents a truck side bearing bridge. A bearing plate 8 is mounted upon one of said bridges, preferably the body side bearing bridge 6. A bearing 9 comprises a base casting 10, a cradle 11, a

35 roll 12 and an axle 13. The base casting 10 is in general shape a hollow sphere truncated above its horizontal axis, as illustrated in Fig. 3 of the drawings. At its base it is provided with spaced apart downwardly

40 extended flanges 14, 14 adapted to engage the sides of the side bearing bridge to which it is attached by suitable means, preferably the rivets 15, 15 passing through said bridge and the flanges 14. At either end of the

45 recess 16 formed between the flanges 14 the base casting is provided with outwardly extended shoulders 17, each of said shoulders being adapted to rest upon the upper face 18 of the side bearing bridge to which the 50 bearing is applied. The hollow base casting is preferably constructed with a comparatively short, straight, internal face at either end, as indicated at the numerals 19, 19 in Fig. 2 of the drawings, to prevent the rota-

tion of the cradle 11 in a horizontal plane 55 therein.

The cradle 11 is of a general circular shape in horizontal plane, the edges 20, 20 of said cradle being shaped to conform with the curvature of the internal adjacent 60 faces of the base casting, the ends 21, 21 of said cradle being preferably straight, however, to conform to the adjacent internal end faces 19, 19 of the base casting. The cradle 11 is provided with a substantially central 65 vertical opening 22 adapted to receive the roller 12. At either side the cradle is provided with a perforation 23 within which the ends of the axle 13 are received, the said axle being extended transversely of the 70 side bearing bridge and passing through the perforation 24 provided in the roller 12. At either end the perforation 24 in said roller receives a bushing 25, which in preferable construction is cast integral with the 75 roller 12. The bushings 25 are preferably of comparatively soft metal, and the axle 13 is preferably hardened.

The hollow in the base casting within which the cradle and roller are received is 80 designated by the numeral 26. The opening 27 at the upper side of the base casting is of lesser width than the diameter of the hollow 26 so that when the cradle is mounted within the base casting it cannot be removed except 85 through rotating the cradle until one end of the same is within the opening 27, whereupon the cradle may be withdrawn. The hollow 26 in the base casting is provided with a plurality of drain holes 28, 28 to permit the discharge of any foreign material 90 that may enter the hollow 26.

In assembling the parts of the bearing the roller 12 is placed in the opening 22 in the cradle 11, and the axle 13 inserted through 95 one of the perforations 23 in the cradle and through the roller 12 until the axle is in its proper position, as illustrated in Fig. 3 of the drawings, whereupon one end of the cradle is inserted in the hollow 26 in the base casting 100 10, and rotated therein to a horizontal position. The base casting is then mounted upon one of the side bearing bridges, the bridge passing through the recess 16 between the flanges 14 and entering the lower portion of the hollow 26, forming at either edge 105 a shoulder 29 to limit the rotary movement of the cradle sufficiently to prevent either

end thereof from rotating into the opening 27 in the base casting. The roller 12 is adapted to be engaged by the bearing plate 8.

5 It will be observed that the cradle 11 is in sliding engagement with the base casting 10 in the hollow 26 thereof, and adapted to automatically adjust itself in relation to the bearing plate 8 when the same engages the 10 roller 12.

I claim:—

1. In a side bearing for railway cars, a bearing member comprising a hollow spherical casting, a slideable cradle mounted there- 15 in, and a roller mounted in the cradle.

2. In a side bearing for railway cars, in combination, an open hollow base casting, a cradle rotatably mounted therein, an axle passing through the cradle, a roller mounted 20 on said axle, the opening in the base casting being of a lesser width than the diameter of the hollow therein, the cradle being removable when one side thereof is rotated into the said opening in the base casting and held 25 in position when the sides of the cradle are arranged below said opening.

3. In a side bearing for railway cars, an open hollow base casting, a rotatable cradle therein, a roller and an axle therefor, the cradle having an opening to receive the roller, the cradle having perforations at the 30 sides of said opening to receive the axle, the opening in the base casting being of lesser width than the diameter of the hollow, the cradle being removable when one side thereof is rotated into the opening of the base casting and held in working position when the sides are moved to positions out of alignment with said opening.

40 4. In a railway car, in combination, a side bearing, bridge, a hollow base casting, a cradle rotatably mounted therein, and a roller mounted in the cradle, the bridge passing through the hollow portion of the 45 base casting and forming shoulders to limit the rotation of the cradle.

5. In a side bearing for railway cars, in combination, a base casting having a substantially spherical hollow portion with an 50 opening therefrom of lesser width than the diameter of the hollow portion, a cradle rotatably mounted in the base casting and in sliding engagement therewith, a roller

mounted in the cradle, and means to limit the rotation of the cradle. 55

6. In a side bearing for railway cars, in combination, a base casting having a substantially spherical hollow portion with an opening therefrom of lesser width than the diameter of the hollow portion, a cradle rotatably mounted in the base casting and in sliding engagement therewith, a roller mounted in the cradle, and shoulders in the hollow portion to limit the rotation of the cradle. 60

7. In a side bearing for railway cars, in combination, a base casting having a substantially spherical hollow portion with an opening therefrom of lesser width than the diameter of the hollow portion, a cradle rotatably mounted in the base casting and in sliding engagement therewith, a roller mounted in the cradle, and removable shoulders in the hollow portion of the base casting 70 to limit the rotation of the cradle. 75

8. In a side bearing for railway cars, in combination, a base casting having a substantially spherical hollow portion with an opening therefrom of lesser width than the diameter of the hollow portion, a cradle rotatably mounted in the base casting and in sliding engagement therewith, a roller mounted in the cradle, removable means to limit the rotation of the cradle, and means to limit the rotation thereof to the vertical 80 plane of the axis of the roll. 85

9. In a side bearing for railway cars, the combination with a hollow base casting, of a cradle mounted therein, said casting and cradle having co-operating curved faces permitting slideable movement between the parts, and means for permitting removal of the cradle from the casting upon rotation of the cradle to a position substantially at right angles to its normal operative position. 90 95

10. In a side bearing for railway cars, the combination with a base casting having a hollow portion provided with spherical surfaces, of a roller carrying cradle having spherical ends mounted in said casting and bodily movable with respect thereto about a horizontal axis. 100

JOHN F. O'CONNOR.
